UNITED STATES PATENT OFFICE.

THOMAS F. McGEE, OF NEW YORK, N. Y.

DIAPER.

1,088,355.

Specification of Letters Patent. Patented Feb. 24, 1914.

Application filed December 20, 1912. Serial No. 737,911.

To all whom it may concern:

Be it known that I, THOMAS F. McGEE, of New York, county of New York, and State of New York, have invented certain new and useful Improvements in Diapers, of which the following is a specification.

This invention relates to diapers and has for one of its objects the provision of a diaper which is adapted to be secured in position on an infant without the use of pins or other fastening devices liable to injure the infant.

Another object is to provide a diaper having fastening means adapted to be attached to the shirt and stockings of the infant and hold the same, as well as the diaper, in position.

Another object is to provide a diaper formed of a plurality of thicknesses of fabric sewed together to form an envelop or casing in which is arranged a pad of waterproof fabric, the pad being secured in position without the use of pins.

Other objects and the features of novelty will be apparent from the following description, taken in connection with the accompanying drawings, of which—

Figure 1 is a perspective view of a diaper embodying my invention, and showing the manner it is secured in position; and Fig. 2 is a plan view of the diaper shown in Fig. 1 as it appears when spread out.

Referring to the drawings, and more particularly to Fig. 1, it will be observed that I have illustrated a portion of the body of an infant having arranged thereon a shirt 10 and a stocking 11. A diaper consists preferably of a casing, formed with two thicknesses of fabric sewed together at all of their edges except the back edge 14. The fabric is preferably cut in the form of an octagon, the front edge of which is at 15, and the edges surrounding the legs at 16 and 17 respectively. When the diaper is placed in position the edges 18 and 19 are arranged approximately over the loins and adjoin, respectively, the edges 20 and 21, the flaps 22 and 23 which are arranged on the latter edges being placed as shown in Fig. 1 and thereby closing the opening which would otherwise exist at these points.

For the purpose of securing the diaper in position, without the use of pins or other more or less dangerous fastening devices, I have provided the edge 18 with the ordinary garter clasps 24 and 25 which are secured to

straps 26 and 27, respectively. The edge 19 is similarly provided with clasps 28 and 29 which are secured to straps 30 and 31, respectively. The edges 20 and 21 are provided with any suitable form of attaching loops of devices adapted to receive the straps 26, 27, 30 and 31, and in the form of the invention illustrated these loops are provided by sewing along the edges 20 and 21, respectively, the tapes 32 and 35, having the free or unsewed portions 33, 34, 36 and 37.

The diaper, when placed in position as shown in Fig. 1 is secured by passing the straps 26 and 30 through the loops 33 and 36 respectively and the clasps 24 and 28 attached to the shirt or other waist garment. The straps 27 and 31 are passed through the loops 34 and 37, respectively, and the clasps 25 and 29 are attached to the stockings. This arrangement, as will be readily understood, effectively secures the diaper in position and at the same time holds the stockings and shirt so that the one set of fastening devices secures all of these garments. When the infant does not wear stockings, or when, for any reason, it is not desired to attach the clasps 25 and 29 to the stockings they may be attached to the tabs or straps 38 and 39, respectively, and thus secure the diaper. The clasps 24 and 28 may be similarly attached to the tabs 40 and 41, when it is not desired to attach them to the shirt.

For the purpose of rendering the diaper waterproof I insert therein, a pad 42 of waterproof material and secure this pad, without the use of pins, by means of a clasp 43 secured to the pad and attached to a tab 44 between the folds of the fabric at the edge 15; and also by loops 45 and 46 through which the straps 26 and 30, respectively, are passed, as shown in Fig. 1.

Having thus described the invention what is claimed as new is:

1. An article of the class described, comprising a casing having an open edge, a waterproof pad arranged within the casing, readily detachable means arranged within the casing at a point remote from said open edge and adapted to secure the pad to the casing, and means extending through said open edge for securing the pad.

2. An article of the class described, comprising a casing having an open edge, a waterproof pad arranged within the casing, and readily detachable means at said open

edge and within the casing, at a point remote from said open edge, for securing said pad in position.

3. An article of the class described, comprising a casing having an open edge, a waterproof pad arranged within the casing, means within the casing for securing the pad at the edge opposite said open edge, securing means for the pad extending through said open edge, and means on the exterior of the casing for fastening said last-mentioned securing means.

4. A diaper having coöperating attaching devices on opposite edges thereof adapted to be connected together and attached to a waist garment and stockings for the purpose of securing the diaper about the body of the wearer and holding said waist garment and stockings in position.

5. An article of the class described comprising a suitably formed piece of fabric having pairs of coöperating edges adapted to meet and be secured together over the loins of the wearer, and flaps secured to one of each of said pairs of edges for closing the opening between the same and the adjoining edges.

6. An article of the class described comprising a suitably formed piece of fabric having pairs of coöperating edges adapted to meet and be secured together, flaps secured to one of each pair of edges, for closing the opening between the same and the adjoining edges, loops arranged on one of each of said pairs of edges, and clasps secured to the adjoining edges and adapted to be passed through said loops and secured to a garment of the wearer, as and for the purpose described.

7. An article of the class described comprising a suitably formed piece of fabric having pairs of coöperating edges adapted to meet and be secured together, loops arranged on one of each of said pairs of edges, and clasps secured to the adjoining edges and adapted to be passed through said loops and secured to a garment of the wearer, as and for the purpose described.

8. An article of the class described comprising a suitably formed piece of fabric having pairs of coöperating edges adapted to meet and be secured together, loops arranged on one of each of said pairs of edges, clasps secured to the adjoining edges and adapted to be passed through said loops, and straps secured to the fabric adjacent said loops and adapted to have said clasps secured thereto to hold the fabric in position on the wearer.

9. An article of the class described comprising a substantially octagon shaped piece of fabric, opposite edges of which are adapted to constitute the front and back portions of the upper edge, flaps secured to the edges adjacent one of said opposite edges, loops arranged adjacent the edges adjoining one of said opposite edges, and means secured adjacent edges remote from said last-mentioned opposite edge and adapted to be passed through said loops and secured as and for the purpose described.

In testimony whereof I affix my signature in presence of two witnesses.

THOMAS F. McGEE.
